US0D1061463S

(12) **United States Design Patent** (10) **Patent No.:** **US D1,061,463 S**
(45) **Date of Patent:** **** Feb. 11, 2025**

(54) **HEAT SINK**

(71) Applicant: **Roy Burke McGovern, Jr.**, Corning, NY (US)

(72) Inventor: **Roy Burke McGovern, Jr.**, Corning, NY (US)

(**) Term: **15 Years**

(21) Appl. No.: **29/841,932**

(22) Filed: **Jun. 9, 2022**

(51) **LOC (15) Cl.** **13-03**

(52) **U.S. Cl.**

USPC **D13/179**

(58) **Field of Classification Search**

USPC D13/179, 182; D23/358, 370, 379, 411, D23/412; D14/435

CPC H01L 23/367; H01L 23/3672; H01L 23/4093; H01L 23/467; F28F 2215/00; F28F 2215/08

Primary Examiner — Brett Miller

Assistant Examiner — Russell Carnell Smith, Jr.

(57) **CLAIM**

The ornamental design for a heat sink, as shown and described.

DESCRIPTION

FIG. 1 is a perspective view of a first embodiment of the present disclosure;

FIG. 2 is a front view of the embodiment depicted in FIG. 1;

FIG. 3 is a rear view of the embodiment depicted in FIG. 1; FIG. 4 is a top view of the embodiment depicted in FIG. 1; FIG. 5 is a bottom view of the embodiment depicted in FIG. 1;

FIG. 6 is a first side view of the embodiment depicted in FIG. 1;

FIG. 7 is a second side view of the embodiment depicted in FIG. 1;

FIG. 8 is a perspective view of a second embodiment of the present disclosure;

FIG. 9 is a front view of the embodiment depicted in FIG. 8;

FIG. 10 is a rear view of the embodiment depicted in FIG. 8;

FIG. 11 is a top view of the embodiment depicted in FIG. 8; FIG. 12 is a bottom view of the embodiment depicted in FIG. 8;

FIG. 13 is a first side view of the embodiment depicted in FIG. 8; and,

FIG. 14 is a second side view of the embodiment depicted in FIG. 8.

The shading presented in the accompanying drawings is provided merely to highlight the contour of the invention and is not intended to be illustrative of texture or gloss.

1 Claim, 4 Drawing Sheets
